UNITED STATES PATENT OFFICE

2,180,883

FUEL PUMP ASSEMBLY

Philip Lane Scott, Chicago, Ill., assignor to Super
Diesel Tractor Corporation, La Porte, Ind., a
corporation of New York

Application November 12, 1936, Serial No. 110,485

6 Claims. (Cl. 29—149.5)

This invention relates to a means for making, sizing and maintaining the size of a barrel in which a member is mounted for reciprocation. The invention relates, therefore, to a pump or 5 analogous device and to the method of making it.

One object of the invention is to provide a pump or similar combination of barrel and plunger in which the bore in the barrel is made of approximately the right size, is corrected as to 10 roundness and parallelism and is then finally reduced to the proper internal diameter by exerting pressure upon a liner which forms a part of the barrel. Another object of the invention is to provide means for re-sizing the barrel. A 15 still further object is to provide means for taking up wear.

Other objects will appear from time to time in the specification and claims.

The invention is illustrated more or less grammatically in the accompanying drawing, 20 wherein:

Figure 1 is a longitudinal section through a pump, wherein portions of a pump and a pump barrel made in accordance with my invention are shown;

Figure 2 is a sectional detail of a modified form of barrel construction.

Like parts are designated by like characters throughout the specification and drawing.

The numeral 1 designates a portion of a pump housing provided with a cylindrical bore or hollow 2 in the lower end of which may be seated a spring 3 to prevent separation of the parts. The member 1 is provided with lateral projections or ears 4 which are perforated as at 5 for attachment to a suitable base. At its opposite end the pump housing is partially closed in by the portion 6 which may be shouldered as at 7. 8 designates a further or additional part of the pump housing which is provided with a bore 9 generally axially aligned with the bore 2. The details of this section and of the pump in general, including the valves, the inlet and the outlet form no essential part of the invention and are not described in detail. The barrel construction of the present invention might be applied to a large variety of pumps whose details of construction are independent of the barrel construction.

The barrel is formed of two parts, a sleeve or jacket 10 provided at one end preferably with a laterally extending flange 11 which is seated against the shoulder 7 of the member 1. The sleeve may be tapered interiorly as at 12. A liner 13 exteriorly tapered to correspond to the taper 12 of the sleeve 10 is provided and is inserted within the sleeve.

The liner has preferably a cylindrical bore 14 which is flared at one end as at 15 to receive a sealing member 16 a portion of which lies in a corresponding flared portion 17 of the bore 9

of the housing member 8. A piston 18 is mounted for reciprocation within the liner. It may be of any desired shape but in the form here shown is pointed as at 19.

At its opposite end the piston or plunger is provided with a rounded end portion 20 and an annular groove 21 within which a driving plate 22 is fitted. Bearing at one end upon the plate 22 and at the other upon the portion 6 of the housing member 1 is a helical spring 23 which thus surrounds the barrel, that is to say, the sleeve 10 and the jacket 13 and lies within the bore 2 of the housing section 1. A cross head 24 is mounted to reciprocate within the housing section 1 and also surrounds the barrel assembly. A contact member 25 may be removably mounted in a perforation 26 in the closed bottom 27 of the cross head. This member 25 may be shouldered at 28 to be seated in a corresponding shoulder 29 in the cross head. A spring or other member 30 holds the contact member 25 removably in place.

Figure 2 shows a modified barrel construction in which, instead of the interiorly tapered sleeve 10, a cylindrical sleeve 31 is used. Its exterior contour is the same as that of the sleeve 10 and it is seated in the pump housing in the same manner. A liner 32 which corresponds on its exterior to the interior of the sleeve 31 is used. It is made cylindrical without exterior taper. It is made approximately to interior size and is then inserted within the sleeve which is shrunk or otherwise compressed on it to the desired degree to produce the proper internal size of the liner bore.

In manufacture the sleeve may be formed as shown with a tapered bore. The liner which may be of cast iron or other suitable material is made preferably with a tapered exterior corresponding in taper with that of the sleeve. The sleeve is of a material of high tensile strength which, therefore, resists deformation. The bore or hole in the liner is made approximately to size and is then pressed into the sleeve. The bore is normally made slightly larger than necessary and after being seated within the sleeve the liner is driven or pressed further in to close up the bore to the desired diameter. By this means absolutely accurate sizing of the liner bore can be accomplished without the necessity of extremely accurate original work. The bore can be closed down to the desired size with great accuracy and with extreme simplicity by forcing the liner into the sleeve the necessary distance. Thus, since the sizing of the bore of the liner is simply accomplished, the manufacturing problem is simplified and in manufacture the attention may be concentrated upon making holes or bores of proper trueness and surface finish, and the final sizing operation, instead of being ac-

complished as a machining or lapping or similar operation is carried out by forcing the liner into the sleeve until the proper degree of fit between sleeve and plunger is obtained.

5 A further advantage of this device is that after wear occurs and the bore becomes oversize, the liner can be brought again to the proper size. It is necessary merely to force the liner further along the taper within the sleeve and it 10 is resized to the desired dimension.

While there is shown a tapered bore and tapered liner and while with this form of the invention the sizing is accomplished by forcing the liner the necessary distance into the sleeve after it 15 has been made true and given proper roundness and parallelism, it is obvious that the sleeve might be shrunk or otherwise tightened upon the liner to give it the necessary size. Whichever form of the invention is used, the liner can be finished by what may be considered "general shop work", in which it can be readily held to a very few ten-thousandths of an inch. A frequent condition will be that when the bore is properly finished and the plunger inserted there will be a 20 slight clearance between the plunger and the bore, this clearance being of the order of a very few ten-thousandths of an inch, and this clearance is then taken up by exerting pressure on the liner either by forcing it into the tapered bore 25 of the sleeve or by otherwise compressing it within the sleeve.

The liner, whether in the form of Figure 1 or Figure 2, may be initially seated within the sleeve before the liner bore is formed and after that 30 bore has been formed, in the case of the tapered arrangement of Figure 1, the liner may be further driven in to complete the sizing operation or, in the form of Figure 2, the shrinking or other operation necessary to compress the liner 35 to proper size may be carried out.

40 Heretofore an accurate mating between a plunger and barrel in a packingless pump, that is to say, in which the main sealing effect is obtained by the nicety of fit between a plunger and 45 barrel of relatively hard materials rather than by soft and easily compressible materials, has proved a very serious problem. General practice has involved hand lapping operations to extreme accuracies which has proved both costly and required 50 excessive amounts of time. This is because no way has previously been known to handle these hard materials except by some form of cutting or abrasion. My invention overcomes this difficulty 55 in that even though the materials are hard they do have slight elasticity and I am taking advantage of this slight elasticity to change the size a mirute amount which, however, is sufficient to produce the desired fit.

60 In forming the pump and in adjusting the relative position of the liner and sleeve to accomplish the final size of the bore of the pump, or to readjust it for wear after use, it is to be understood that the adjustment of the liner and sleeve may be such as to produce first too tight 65 a fit and movement of the parts may, when this occurs, be reversed to permit sufficient expansion on the part of the liner to produce the proper size of bore. The pump barrel as an article of manufacture is claimed in my co-pending application, Serial No. 110,484, filed November 12, 1936. 70 The method of making and assembling the pump barrel and associated parts is claimed herewith.

I claim:

1. The method of sizing a liner in a multi-part pump barrel, which includes the steps of forming a hollow liner with tapered exterior, forming a hollow sleeve with correspondingly tapered interior, forcing the two together axially and thereby decreasing the internal size of the liner to the desired final size. 5

2. The method of sizing a liner in a multi-part pump barrel, which includes the steps of forming a hollow liner with tapered exterior, leaving the 10 interior size thereof greater than that finally necessary, forming a hollow sleeve with correspondingly tapered interior, forcing the two together axially and thereby substantially uniformly decreasing the internal size of the liner to the 15 desired final substantially uniform size.

3. The method of sizing a liner in a multi-part pump barrel and guiding assembly which includes the following steps: making a hollow liner, forming through said liner a round, straight hole to 20 a slightly variable, over-sized diameter, making a cooperating compression member, placing said compression member about said liner, moving the compression member with respect to the said liner, and thereby compressing the liner and reducing 25 by said compression the outside diameter of the liner to a minute amount and, also, thereby reducing the diameter of the bore of said liner uniformly, and holding the stresses set up within both the liner and the compression member well 30 within the elastic limits of the materials, and maintaining the inner walls of the liner bore straight during such compressive step.

4. The method of making and sizing a liner in 35 a multi-part pump barrel assembly which includes the steps of making a liner, boring a round, straight hole axially through said liner, making and placing about said liner a co-operating compression member, moving the compression member axially with respect to said liner and there- 40 by exerting compression upon said liner and decreasing the internal diameter of the liner.

5. The method of making and of sizing a liner in 45 a multi-part pump barrel assembly which includes the following steps: making a liner, making a round, straight-sided, slightly over-sized hole from end to end of said liner, making a compression member, placing said compression member about said liner in contact therewith, moving the compression member with respect to said 50 liner and exerting as a result of such movement a uniform compression upon said liner and thereby reducing uniformly the internal dimension of the liner, and simultaneously maintaining the inner walls of the liner straight. 55

6. The method of sizing the bore of a liner in 60 a multi-part pump barrel assembly, having a liner, a jacket therefor, and a plunger return, and adapted to be reciprocated therein, which method includes the following steps: machining a bore in the liner to be slightly over-size with respect to the said plunger, machining a tapered exterior wall on the liner, machining a mating tapered interior wall on the jacket, forcing the jacket and the liner together by relative longitudinal movement along the axis of the tapers, and compressing the liner by means of the jacket uniformly along radial lines, and reducing the radial dimensions of the liner uniformly, and continuing the said movement until a predetermined running fit between bore and plunger is reached. 7

PHILIP LANE SCOTT.
